CARTON STACKING BRACKET FOR PALLETS OR THE LIKE

Robert Lee Griffith, 501 Russell St.,
Covington, Ky. 41011

Original design application Aug. 21, 1969, Ser. No. 18,794,
now Patent No. 220,166, dated Mar. 16, 1971. Divided
and this application July 15, 1970, Ser. No. 23,949

Term of patent 14 years

Int. Cl. D8—03

U.S. Cl. D8—233

FIG. 1

FIG. 2

FIG. 3

FIG. 1 is a side perspective view of a carton stacking bracket for pallets or the like showing my new design;
FIG. 2 is a top plan view thereof; and

FIG. 3 is a side elevational view thereof.

This is a division of design application Ser. No. 18,794, filed Aug. 21, 1969, and now Pat. No. D-220,166.

I claim:

The ornamental design for a carton stacking bracket for pallets or the like, as shown.
